DESIGN FOR AN ELECTRICAL APPLIANCE PLUG CONNECTER

Clifford Brooks Stevens, Milwaukee, Wis., assignor to Cutler-Hammer, Inc., Milwaukee, Wis., a corporation of Delaware

Application March 10, 1938, Serial No. 75,717

Term of patent 14 years

To whom it may concern:

Be it known that I, Clifford Brooks Stevens, a citizen of the United States and a resident of Milwaukee, in the county of Milwaukee and State of Wisconsin, have invented a new, original, and ornamental Design for an Electrical Appliance Plug Connecter, of which the following is a specification, reference being had to the accompanying drawing, forming part thereof.

Figure 1 is a front elevational view showing one face of an electrical appliance plug connecter incorporating my new design.

Fig. 2 is a side elevational view thereof. Figures 3 and 4 are bottom and top plan views, respectively, of said connecter.

Fig. 5 is a sectional view on line 5—5 of Fig. 1. Fig. 6 is a fragmentary sectional view on line 6—6 of Fig. 1.

I claim:

The ornamental design for an electrical appliance plug connecter, substantially as shown.

CLIFFORD BROOKS STEVENS.
